UNITED STATES PATENT OFFICE.

JOSEPH V. KNIGHT, OF LYNN, MASSACHUSETTS.

BURGLAR-ALARM.

SPECIFICATION forming part of Letters Patent No. 256,145, dated April 11, 1882.

Application filed January 24, 1882. (No model.)

To all whom it may concern:

Be it known that I, Jos. V. KNIGHT, of Lynn, county of Essex, and Commonwealth of Massachusetts, have invented certain new and 5 useful Improvements in Burglar-Alarms; and I do hereby declare that the following is a full, clear, and exact description of the same.

The object of this invention is to obtain a simple, cheap, and reliable automatic alarm-bell for use in stores, offices, and houses, for application to doors, shutters, and other swinging devices in such manner that when the door or shutter, as the case may be, is opened the moving of the same will release a hammer and 15 cause the bell to sound and give the desired alarm.

The invention consists in matters of construction hereinafter fully described and claimed.

20 In the accompanying drawings, Figure 1 shows a side elevation of my improved burglar-alarm. Fig. 2 is the same as Fig. 1 with the face-plate removed to show the inside mechanism. Fig. 3 shows the alarm in combination 25 with a door.

The case A is provided with three cross-bars, B, C, and D, designed to support the operative mechanism. The pinion e is pivoted to the cross-bar D, and is revolved by the cross-spring 30 d, arranged about its axle, as shown in Fig. 2. Said pinion e engages with and turns the smaller pinion a, thereby giving motion to the escape-wheel f, which in turn operates the escapement h so as to reciprocate the hammer n and 35 sound the bell E, all in an obvious manner. A pawl has its end pivoted to the ear 2 and engages with the pinion e, so as to lock the pinion when desired, as referred to hereinafter. The lever-ratchet 3 is centrally pivoted to the 40 cross-bar C. Said ratchet engages at one end with the pinion e and at its opposite end with the button 4, and is disengaged from the pinion e by operation of the spring 5. Fig. 2 shows the mechanism set ready for an alarm, 45 in which condition the ratchet 3 appears engaged with pinion e. The spring 5, being depressed by the ratchet, is prevented from acting so long as the end of the ratchet is held down by the button 4.

50 The parts are protected from dust or injury

by a face-plate, which is perforated, as shown in Fig. 1, being thereby better adapted to the transmission of sound.

The alarm is attached to the door or other swing device by screws, as shown in Fig. 3. 55 It is set for operation through suitable holes, 6, 7, and 8, made in plate H. By reason of a key fitted in an obvious manner the spring d is first wound up. The ratchet 3 is then depressed till its inner end engages with the pinion e, whereupon the door is closed with the outer end of the ratchet 3 under the button 4. It will now be understood that should the door be opened sufficiently to move the end of ratchet 3 away from the button 4 the spring 5 would 65 operate to release the pinion e, and the alarm would be given.

If it is desired to open the door without giving an alarm, it is only necessary to insert the key in hole 6 and throw the ratchet into 70 engagement with the pinion e, whereupon the door may be opened, and although the ratchet 3 is disengaged from the pinion e, the pinion is still locked by the ratchet 1, so that no alarm will be sounded.

From the foregoing it will appear that by this my invention I am enabled to make a compact, simple, and reliable alarm-bell suitable for application to doors or other swinging devices where it is desired that an alarm 80 should be given upon the opening of the same.

Having thus described my invention, what I claim is—

1. In a burglar-alarm, the combination of a click-spring, gearing e a f, an escapement, h, 85 a hammer, and a bell with a pivoted spring-pawl, 3, and a stop or button, 4, all constructed and adapted to be operated substantially as described.

2. In a burglar-alarm, the combination of 90 the pinion e, the spring, gearing e a f, escapement h, hammer, and bell with the spring-pawl 3, the button 4, and the locking-pawl 1, substantially as described.

In testimony whereof I have signed this 95 specification in presence of two witnesses.

JOS. V. KNIGHT.
